[57] CLAIM

I claim the ornamental design of a plant support, as shown and described.

DESCRIPTION

FIG. 1 is a perspective view of the invention; FIG. 2 is a front view of the invention; FIG. 3 is a left side view of the invention; FIG. 4 is a rear view of the invention; FIG. 5 is a top view of the invention; FIG. 6 is a bottom view of the invention; FIGS. 7-9 are perspective views of the invention showing various configurations of the resilient arms as positioned by the user;

FIG. 10 is a perspective view of the invention used in a stacked tandem showing one configuration of the resilient arms as positioned by the user; and,

FIG. 11 is a perspective view of the invention used in a side-by-side tandem showing one configuration of the resilient arms as positioned by the user.

The right side view of the invention would be a mirror image of the left side view of FIG. 3.

The broken line showing is for illustrative purposes only and forms no part of the claimed design.
